UNITED STATES PATENT OFFICE

2,488,093

DOUBLE-ACTING TWO-STROKE INTERNAL-
COMBUSTION ENGINEMark Ferdinand Meinertz, Copenhagen, Denmark
Application May 23, 1946, Serial No. 671,774
In Denmark May 17, 1945Section 1, Public Law 690, August 8, 1946
Patent expires May 17, 1965

3 Claims. (Cl. 123—61)

1

Double-acting two-stroke engines are known with transverse or reverse scavenging at both cylinder ends. These engines are simple because the admission and exhaust can be controlled by the working piston alone, for which reason there will be a minimum number of movable parts, but on account of the imperfection of the scavenging system they have comparatively small mean pressures and consequently their weight and the space they take up are comparatively large as compared with the effect they yield. Furthermore they are strongly subjected to very unfortunate unequal heat stresses on account of the uneven heating of the port sections of the cylinders.

Double-acting two-stroke engines are also known with longitudinal scavenging at both cylinder ends, the scavenging ports being controlled by the working piston while the exhaust occurs through exhaust members in the form of pistons or slide valves mounted in both cylinder ends.

The application of slide valves necessitates separate drives for these from the crank shaft which entails that the length of the engine and thereby its weight get comparatively large in spite of the high mean pressure made possible by the longitudinal scavenging.

Various constructions of double-acting two-stroke engines have been proposed with scavenging ports at the middle of the cylinders and exhaust valves at the cylinder ends, but as far as we know these constructions have not hitherto been carried into practice on account of difficulties as regards the cylinder design and especially the construction of the cylinder end through which the piston rod passes. In accordance with one of the earlier proposals an exhaust valve was to be mounted in this cylinder end so as to surround the piston rod, but such a construction is inapplicable in practice because the valve gets very heavy and demands far too large forces for being actuated, and likewise it is impossible to overhaul it without a very large work of disassembling.

In accordance with another proposal it has been attempted to avoid these difficulties by mounting the exhaust valve of the bottom end in a special way in the cylinder cover, i. e. to the side of the passage means for the piston rod and directed obliquely in relation to the latter. This construction, however, in part suffers from the drawback that the scavenging of the bottom end will not get very effective on account of the unilateral exhaust and the central piston rod, in part it entails on account of the unsym- 55

2

metrical construction, the disadvantageous properties of which are further intensified by the exhaust valve getting comparatively large, a so unequal load on the cylinder cover and the liner on account of the combustion pressure and the heat stresses that the construction must be considered inapplicable.

The purpose of the present invention is to construct a double-acting two-stroke engine with longitudinal scavenging in both cylinder ends, in which the advantages of the said known engine types are combined, while their drawbacks are avoided, so that an engine type is obtained which is suited for stationary engines and engines for vessels for large and very large outputs per cylinder unit, and which offers a combination expedient for practical purposes of slight weight and small requirements as to space per effect unit, simplicity as to construction, good load conditions 20 with regard to combustion pressures and heat stresses, besides reliability and easy access for inspection and dismounting.

The engine in accordance with the invention is of the kind which has longitudinal scavenging of both cylinder ends through piston-controlled scavenging ports in a scavenging port section serving as central part in the cylinder and poppet valve controlled exhaust openings in both cylinder ends, of which ends the cylinder top has only a single centrally mounted exhaust valve, and the invention is characterized in that the bottom end of the cylinder—i. e. the cylinder end through which the piston rod passes—has two obliquely mounted exhaust valves placed symmetrically in relation to the piston rod passage means, and in that each of the two cylinder ends consists of a bell-shaped body of steel made in one piece, which body is by a heavy clamping flange at the open end clamped 40 to the central part, and which at some distance outside the closed end has a light, preferably substantially plate-shaped collar, through which the passage means for exhaust valves, fuel valves, starting valves, etc. and piston rod stuffing box 45 are carried into the closed cylinder end, which collar along its outer edge bears against and forms the termination of a cooling jacket enclosing the said cylinder end, while in a way known per se the central part forms a longitudinal girder serving as scavenging air box, which girder transmits the combustion forces to the remaining parts of the framing and from which the cylinder ends project so as to be able to expand freely upwards and downwards.

By this construction a scavenging in the bot-

tom end may be attained which is just as effective as the scavenging in the top end, and all difficulties in making especially the bottom cylinder able to withstand combustion pressures and heat stresses are eliminated. The fact is that the closed, bell-shaped cylinders made in one piece are in themselves very strong, and the symmetrical mounting of the exhaust valves at the closed end of the bottom cylinder ensures an even and uniform heating of the latter, and likewise there will be room enough for arranging cooling spaces. By separate cylinder covers being dispensed with, the usual very heavy clamping means for the latter are also omitted, and the combustion pressures are transmitted direct through the cylinders to the central part and from there to the stationary framing without the cylinders being prevented from expanding longitudinally.

The outwards-facing ends of the cooling jackets are, as mentioned before, formed by light collars on the cylinders, and these cannot give rise to perceptible heat stresses, as they may be made thin and yieldable. Correspondingly the inwards-facing ends of the cooling jackets may in accordance with the invention bear on light collars which are cast in one piece with the cylinders and are situated in the vicinity of the clamping flanges of the latter. The cooling jacket proper may then consist of a simple cylindrical tube which is clamped to one collar and has a movable sealing against the edge of the other collar.

In double-acting internal combustion engines it is known to provide the running surfaces of the cylinders with a tripartite liner of a material with good running properties, such as cast iron. This known measure may in the engine in accordance with the invention be taken in an especially advantageous way, the composite wearing liner consisting of two simple cylindrical liners of a very slight thickness of material, which are pressed or shrunk each into its own of the bell-shaped steel cylinders, while the central liner part situated in the scavenging air box is of a considerable thickness of material and along the whole of its circumference is provided with evenly distributed scavenging air ports. By this arrangement is attained that the two liner parts which are subjected to wear get short and thin and of a very simple construction, so that they can be given the proper uniform hardness conditioning a slight wear, and also may be replaced without high costs and without it being necessary to change the central liner part. This may therefore be given a thickness of material that is sufficiently large for attaining a good control of the scavenging air, and the expensive work done at the milling out of the scavenging ports is not wasted at the replacement of the wearing liners.

While the control of the exhaust valve of the top cylinder does not give rise to difficulties, it is not possible without further ado to control the two exhaust valves of the bottom cylinder from the same cam shaft because these valves are mounted one on each side of the piston rod, and have their valve spindles pointing obliquely outwards and downwards in different directions. The invention also comprises an especially suitable actuating mechanism for the exhaust valves of the bottom cylinder, which mechanism is characterized in that a push rod actuated by a cam disk mutual to both valves is led down into the closed crank case of the engine and from there actuates the valve spindles through vertical push rods which project upwards from the crank case,

each one under its valve spindle, and actuate the latter through approximately hammer-shaped rocking levers.

In an expedient embodiment of this actuating mechanism the pressure rods and levers situated in the crank case have only loose pressure connections which will need no lubrication except the oil splash in the crank case.

The invention is illustrated on the accompanying drawing by an embodiment.

Fig. 1 shows a vertical cross section through an engine in accordance with the invention, in part diagrammatically, and

Fig. 2 what is shown in Fig. 1 viewed from the right in part from the outside and in part in section.

On the drawing, which must be supposed to show a single cylinder unit in a multi-cylinder engine, 1 designates a central part of a cylinder, 20 to which a top cylinder 2 and a bottom cylinder 3 are bolted by means of heavy clamping flanges 5 and 6 respectively. The central part 1 together with the central parts of the adjacent cylinder units form a longitudinal girder, from which the top and bottom cylinders project so as to be able to expand freely upwards and downwards respectively, and which by means of bolts and nuts 31 is secured to frames 4 mounted transversely to the longitudinal direction of the engine, through which frames the combustion pressures are transmitted to the remaining parts of the stationary engine framing which is not shown on the drawing.

35 The top and the bottom cylinders 2 and 3 are made as heavy bell-shaped bodies of evolution of steel and both have at their outermost end a rather large central passage means for an exhaust valve 13 and for the piston rod 16 respectively. These passage means have the form of comparatively heavy tubes co-axial with the bell-shaped cylinder bodies, and they carry at their outwards-facing ends light, substantially plate-shaped collars 7 and 8 respectively, the outer diameter of which is somewhat larger than the outer diameter of the cylinder bodies. The collars 7 and 8 are machined on their outer edges and form cylindrical bearing surfaces for tubular cooling jackets 9 and 10 respectively. These 40 are bolted to corresponding light collars 11 and 12 at the inwards-facing ends of the cylinders.

45 Through the collars 7 and 8 passage means are carried for the usual cylinder fittings, such as fuel valves, starting air valves, indicator valves, 50 safety valves, etc. These passage means consist of light tubes which are cast in one piece with the cylinder bodies and the collars and the thickness of material of which is chosen so that they cannot give rise to heat stresses. A single passage means of that kind is shown by 17 in Fig. 1. The bottom cylinder furthermore contains two 55 corresponding passage means for exhaust valves 14 which are mounted symmetrically in relation to the piston rod and directed obliquely in relation to the axis of the latter. By this mounting of the exhaust valves it gets possible to obtain a sufficiently large exhaust area without the combustion space getting any detrimental pockets.

60 The exhaust valve 13 of the top cylinder is controlled in the usual way from a cam shaft 18 by means of a push rod 19 and a rocker arm 20. The exhaust valves of the bottom cylinder are controlled from the same cam shaft through a push rod 21 which is led down into the closed crank case 30 of the engine, where it actuates a bell

crank 23 which is rotatable around a stationary spindle 22. The other arm of the said bell crank through a rod 24 actuates another bell crank 25 which is secured to a spindle 26 which is journalled in the crank case and furthermore carries a lever of the second order 25'. This and the other arm of the bell crank 25 actuate vertical push rods 27 which through guides 29 are carried up through the upper wall of the crank case directly below the freely projecting ends of the valve spindles, on which they act through hammer-shaped rocking levers 28 that are pivotal around stationary pins. The whole actuating mechanism thus contains only loose pressure connections and need no other lubrication than the oil splash in the crank case. Most of the actuating mechanism lies hidden in the crank case and thus does not prevent access to the downwards-facing end of the bottom cylinder and to the stuffing boxes 15 and 36 of the piston rod.

The running surface of the assembled cylinder is formed by cast iron liners, i. e. one liner part 32 inserted in the central part 1 and two liner parts 34 and 35 inserted in each cylinder body. The central liner part 32 is made rather heavy so that the scavenge ports 33 milled out in its material become long enough to effect a good control of the scavenge air. The outer liner parts 34 and 35 are on the other hand quite thin and are quite concealed in the cylinder bodies, in which they are secured by pressing or shrinking. They may, as shown, have a small edge for fixing their position at the insertion but are otherwise made of a mainly uniform thickness of material and without heavy flanges. They are therefore cheap to replace, while the central liner part 32 need not be replaced as it does not get perceptibly worn.

The invention is not bound to the embodiment shown and described, the details of which may be varied in different ways. By way of example the cooling jackets of the cylinder bodies may be constructed in other ways than that shown, if only the light collar mounted on the cylinder body is preserved as a termination of the cooling space. The valves may be controlled in other ways than that shown by mechanical, hydraulical, or pneumatic means. The central part of the cylinder may form a coherent girder for several cylinders or may consist of single pieces, bolted or welded together, if so desired and construction of the framing may be another than that shown.

I claim:

1. Double-acting upright two-stroke internal combustion engine having piston-controlled scavenging ports provided in a central cylinder member, bell-like top and bottom cylinder members bolted to said central cylinder member and projecting freely upwards and downwards respectively, exhaust valve means in the upper end of the top cylinder member and two exhaust valves of the poppet valve type mounted in the lower end of the bottom cylinder member symmetrically with respect to the piston rod and with their

valve stems directed downwards and outwards to either side, light plate-like flanges integral with the outer ends of the top and bottom cylinder members and situated a short distance above and below the same respectively, separate cooling jackets enclosing the projecting portions of the top and bottom cylinder members and joined fluid-tight to either of said flanges along the periphery thereof, apertures for exhaust valves and remaining cylinder accessories being provided through each of said flanges and end of corresponding bell-like cylinder member.

2. Double-acting two-stroke internal combustion engine as claimed in claim 1 having light flange-like collars integral with and situated in the vicinity of the inner end of top and bottom cylinder members respectively and completing the cooling jacket of each.

3. Double-acting two-stroke internal combustion engine having piston-controlled scavenging ports provided in a central cylinder member, bell-like top and bottom cylinder members bolted to said central cylinder member and projecting freely upwards and downwards respectively, exhaust valve means in the upper end of the top cylinder member and two exhaust valves of the poppet valve type mounted in the lower end of the bottom cylinder member symmetrically with respect to the piston rod and with their valve stems directed downwards and outwards to either side, light plate-like flanges integral with the outer ends of the top and bottom cylinder members and situated a short distance above and below the same respectively, separate cooling jackets enclosing the projecting portions of the top and bottom cylinder members and joined fluid-tight to either of said flanges along the periphery thereof, apertures for exhaust valves and remaining cylinder accessories being provided through each of said flanges and end of corresponding bell-like cylinder member, a camshaft with a cam operating a push rod, a system of levers and rods enclosed in the crank case and actuated by said push-rod, and terminating with two push-rods projecting substantially vertically from the crank case in the immediate vicinity of the lower ends of said valve stems, pivoted hammer-like levers being interposed between the upper ends of said push-rods and the lower ends of said valve-stems.

MARK FERDINAND MEINERTZ.
